ATTORNEY

UNITED STATES PATENT OFFICE

CICERO C. BROWN, OF HEBRONVILLE, TEXAS

WELL HEAD EQUIPMENT

Application filed June 27, 1929. Serial No. 374,113.

This invention appertains to well head equipment generally, and has for its main object to provide for a combined tubing head, tubing hanger and syphon device, which 5 operate in a manner to enable an operator to readily and easily control the flow of fluid (water, gas and/or oil) from a well, especially a well flowing in production, as well as to effect the drawing off of water accumulations at the bottom of the well whenever necessary.

Another object of the invention is to provide for an equipment of the class set forth, which will include a master valve capable of 15 being operated to close off the flow of gas and/or oil while the tubing is in the well casing, and whereby all gas and/or oil will be confined in the well casing and tubing below the master valve, making it possible to change 20 any fitting or valve on the well without removing the tubing or syphon valve or dropping the same for the purpose. The said fittings and valves thereof are located above the master valve and are much worn and deteriorated, so as to be ineffective, by the sand and grit ordinarily carried by the oil and caused thereby to impinge with much force 25 on the metal parts by which the oil is conducted.

A further object of the invention is to provide an equipment as hereinbefore characterized, whereby the oil flow tubing or syphon pipe may be readily and easily parted in 30 place in order to permit of the closing of the master valve as aforesaid.

A still further object of the invention is to provide a novel form of hanger for effectively suspending the tubing or syphon pipe downwardly of a well casing, but which readily allows for the gas and/or oil to pass upwardly 35 of the casing about the oil flow tube when the syphoning action of the tubing or pipe is not required.

With the foregoing and other equally important objects and advantages in view, the invention resides in the certain new and useful combination, construction and arrangement of parts as will be hereinafter more 40 fully described, set forth in the appended

claims, and illustrated in the accompanying drawings, in which:

Figure 1 is a vertical section through the upper end of a well casing and a preferred embodiment of the parts of the invention in 45 assembly and positioned thereon, a portion of the master gate valve being shown in elevation; and

Figure 2 is a horizontal section taken on the line 2—2 of Figure 1.

Referring to the drawings, the embodiment of the invention, as shown therein by way of example, is constituted in a tubular member 10, which is coupled at its lower end to the upper end of a well casing 11, projecting above the ground surface, by means of a nipple or the like 12, and which has an annular seat 13 formed inwardly of the upper end thereof to support thereon a hanger 14 for a syphon or oil flow tubing or permanent or stationary well flow pipe 15 extending downwardly of the casing 10 for the removal of fluid accumulations from the bottom of a well. Ordinarily this tubing is permanent or stationary while the well is producing by 50 its natural flow. It of course would be removed for any necessary repairs, and equipped as a pump barrel in case the well is to be operated by pumping.

This hanger 14 is preferably in the form of a hollow cylindrical body and of a diameter to snugly fit inwardly of the upper open end of the tubular member 10 for supported engagement on the seat 13, and has a concentrically disposed tubular core 16 within the 55 same and supported from the inner wall thereof by radial webs 17 (Figure 2), the latter being equi-distantly spaced apart to provide passageways 18 therebetween, whereby gas and/or oil may pass from the casing upwardly therethrough about the core 16. The well flow pipe 15 is supported from the lower end of the core 16 by having its upper end screw threaded into engagement therewith. The upper end of the core 16 is projected for 60 a slight distance above the hanger body 14 and is flared to form a substantially conical seat 19, the latter to be engaged by the lower substantially conical end of a vertically movable extension 20 of the syphon tubing 15.

The extension 20 may seat on the well flow pipe through the medium of the hanger so as to have communication with the well flow pipe.

5 Supported on the upper end of the tubular body 10, as by having screw threaded engagement with the outer side thereof, is a valve casing 21 in which a horizontal gate or master valve 22 is mounted. The path of 10 movement of the gate valve 22 is in a plane immediately above the upper end of the flared core end 19 of the hanger 14, and the same is actuated from and to a normally opened position by means of a hand wheel 23. The 15 valve casing is preferably formed to provide a vertical partition 24, which divides the interior of the same into two chambers 25 and 26, the chamber 25 having its upper and lower ends opening through the casing, while 20 the partition 24 is horizontally slotted for the passage of the gate valve 22 therethrough.

Secured in the upper open end of the valve casing 21 is a tubing head 27, which has laterally arranged outlets 28 and 29 opening outwardly at the lower chambered end thereof for conveying fluid from the well casing. The upper solid end portion of the head 37 has a vertical bore formed centrally of the same, through which the syphon tubing extension 20 depends. Surrounding the upper end of the bore in the head 27 is an annular seat or gland for the reception of a packing 30 which is compressed about the syphon tube extension 20 by means of a gland element 31, 35 the latter being secured in a set position by means of stud bolts or the like 32, thereby forming a sealing bearing for the flow pipe extension 20 and closing the top of the chamber in the head 27.

40 An annular flange 33 is formed about the upper end of the head 27 to seat thereon a yoke 34, in the upper end of which the hub portion 35 of a hand wheel 36 is journaled. The hub 35 is provided with a centrally disposed vertical bore which is screw threaded to receive therethrough a complementally screw threaded portion 37 of the syphon tube extension 20, the latter having a nippled extension 38 at its extreme upper end for the 45 attachment thereto of a valve controlled conduit (not shown) to convey the fluid to be withdrawn from the well bottom upwardly through the syphon tubing 15 and the extension 20 thereof to a point or points of discharge. The upper nippled end 38 of the extension 20 will preferably be exteriorly screw threaded to first receive thereon a gate valve (not shown) whereby the syphon tubing will be closed except during the normal 50 operation of the well, and also opened whenever it is necessary or desirable to relieve the well of water accumulations therein.

In the operation of the equipment as thus constructed and arranged, the flow of gas and/or oil may be readily controlled from

the master gate valve 22, and, in the normal operation of the well, the gate valve 22 will be opened and the gate valve (not shown) at the upper end of the syphon tubing extension 20 is also open, with the lower end of the latter engaged in the seat 19 at the upper end of the hanger 14. In this condition, gas and/or oil may readily flow upwardly of the casing 11, through the tubular member 10, the passages 18 of the hanger 14, and into the chamber 25 of the valve casing 21, and from thence it will pass through the lower tubular portion of the tubing head 27 and outwardly of the outlets 28 and 29. In the event that it is desired to close the gate valve 22, as for the purpose of repairing or renewing valves or fittings above the same, the hand wheel 36 will be rotated in a direction to part the pipe and lift the syphon tube extension 20 from off the seat 19 of the hanger 14, when the hand wheel 23 will be rotated in a direction to move the gate valve 22 to closed position. With the gate valve 22 in open position, and the lower end of the syphon tube extension 20 supported in the seat 19 of the hanger 14, the well is producing oil through the pipe extension 20. If it becomes desirable or necessary to draw off water accumulations from the bottom of the well, the gate valve (not shown), at the upper end of the syphon tube extension 20 is opened.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

I claim:

1. A head for oil wells having means for attachment to the top of a master gate valve casing, said head having a chamber provided with a side opening for connection with a fluid conduit and a sealing bearing closing the top of said chamber, a flow pipe extension vertically movable in said bearing, a permanent well flow pipe in the well the upper end of which terminates below the valve, the lower end of said pipe extension normally having close communication with the upper end of said permanent well flow pipe to form a continuous conduit, and means to move said pipe extension from said well flow pipe to permit said valve to be closed.

2. A head equipment for oil wells which have a master gate valve and valve casing and a stationary well flow pipe, said equipment having in combination a head provided with means for attachment to the top of said master gate valve casing, said head having a chamber provided with a side opening for connection with a fluid conduit and with a sealing bearing closing the top of said chamber.

- ber, a hanger for supporting said stationary well flow pipe in the well, said hanger having means for attachment to the bottom part of said valve casing and being provided with 5 fluid passages from the well to said valve casing, the lower end of said pipe extension being adapted to seat on the upper end of said stationary well flow pipe to form a continuous conduit, and means to move said pipe extension in said bearing and from said seat to permit said valve to be closed.
3. In a means for controlling the flow of fluid from oil wells, the combination of an oil well casing, a tubular member secured to 15 the upper end of said casing and having a supporting seat, a hanger in said tubular member and resting on said seat, said hanger having a tubular core and vertical passages for fluid, and a seat, a stationary well flow 20 pipe secured to said hanger, a master gate valve and valve casing the latter secured to said tubular member, a head secured to said valve casing above the valve and having an outlet for fluid coming from said hanger, and 25 having a bearing closing the top of said head, a well flow pipe extension vertically movable in said head and adapted at its lower end to fit said seat of the hanger, and means for moving said extension away from the hanger to 30 permit said valve to be closed.
4. In a means for controlling the flow of oil, gas and water from oil wells, the combination of an oil well casing, a tubular member secured to the upper end of said casing 35 and having a supporting seat, a hanger in said tubular member and resting on said seat, said hanger having a tubular core and webs providing vertical passages for fluid, and a seat, an oil flow tube secured to said hanger, a 40 master gate valve and valve casing the latter secured to said tubular member, a head secured to said valve casing above the valve and having outlets for fluid coming from said hanger, and having a sealing bearing closing 45 the top of said head, an oil flow tube extension vertically movable in said head and adapted at its lower end to fit said seat of the hanger and having an external screw thread, a rotatable hub having an internal screw thread 50 engaging said screw thread of the tube extension, and means for holding said hub from vertical movement.
5. A head for oil wells having means for attachment to the top of a master gate valve body, said head having a chamber provided with a side opening for connection with a fluid conduit and a sealing means closing the top of said chamber, a flow pipe extension projecting through said sealing means, a permanent well flow pipe in the well the upper 55 end of which terminates below the valve, the lower end of said pipe extension normally having close communication with the upper end of said permanent well flow pipe to form 60 a continuous conduit, and means to part said 65 pipe at said well flow pipe to permit said valve to be closed.
6. A head equipment for oil wells which have a master gate valve and valve body and a stationary well flow pipe, said equipment 70 having in combination a head provided with means for attachment to the top of said master gate valve body, said head having a chamber provided with a side opening for connection with a fluid conduit and with a sealing means 75 closing the top of said chamber, a hanger for supporting said stationary well flow pipe in the well, said hanger having means for attachment to the bottom part of said valve casing and being provided with fluid passages 80 from the well to said valve casing, the lower end of said pipe extension being adapted to seat on the upper end of said stationary well flow pipe to form a continuous conduit, and means to part said flow pipe at said seat to 85 permit said valve to be closed.
